UNITED STATES PATENT OFFICE.

AMDY CHRESTENSEN, OF COHOES, NEW YORK.

RAIL-JOINT.

SPECIFICATION forming part of Letters Patent No. 753,854, dated March 8, 1904.

Application filed September 12, 1903. Serial No. 172,974. (No model.)

To all whom it may concern:

Be it known that I, AMDY CHRESTENSEN, a citizen of the United States, residing at Cohoes, in the county of Albany and State of New York, 5 have invented new and useful Improvements in Rail-Joints, of which the following is a specification.

My invention relates to a new and useful improvement in rail-joints; and its object is to 10 provide a simple and inexpensive device of this character by means of which the abutting ends of rails may be securely fastened together without necessitating the employment of bolts or other fastening means.

15 A further object is to provide a joint which will support the ends of the rails and prevent pounding thereon by wheels passing thereover.

With the above and other objects in view the 20 invention consists in the novel construction, combination, and arrangement of parts which will be hereinafter more fully described and claimed, and illustrated in the accompanying drawings, showing the preferred form of my 25 invention, and in which—

Figure 1 is a perspective view showing two rails connected by means of my improved joint. Fig. 2 is an enlarged central vertical longitudinal section therethrough. Fig. 3 is a section on line 3 3, Fig. 2.

Referring to the figures by numerals of reference, 1 is the base of a casting, from the side edges of which extend inwardly-projecting flanges 2, which are so shaped as to extend 35 over and fit snugly upon base-flange 3 of a rail 4. Extending upward from the inner edges of the flanges 2 are side plates 5, which are connected at the center by means of an integral block 6. The ends of the rails are provided with rectangular recesses 7, and the area of each of these recesses is approximately equal to one-half the area of block 6. These recesses are so located in the ends of the rails that when 40 said rails are inserted into opposite sides of the casting formed by the base-plate 1, flanges 2, and side plates 5 the opposite sides of the block 6 will be engaged thereby. As this block is integral with the side plates 5, it will 45 serve to support the ends of the rails and pre-

vent them from sagging, thus insuring a 5° smooth joint and preventing pounding by rails passing thereover. The joint is provided with recesses 20 in the sides of the base-plate 1 for the reception of spikes or other securing means, and braces 21 in form of webs are 55 preferably interposed between the flanges 2 and the side plates 5 for preventing the bending or breaking of the said side plates under lateral strain.

It will be seen that the device is extremely 60 simple and inexpensive in construction and will snugly hold rails together without the necessity of employing bolts or other similar fastening means.

In the foregoing description I have shown 65 the preferred form of my invention; but I do not limit myself thereto, as I am aware that modifications may be made therein without departing from the spirit or sacrificing the advantages thereof, and I therefore reserve 70 the right to make such changes and alterations as may fairly fall within the scope of my invention.

Having thus fully described my invention, what I claim as new, and desire to secure by 75 Letters Patent, is—

The combination with rails having base-flanges, and recesses in the adjoining ends of the webs of the rails; of a base-plate below the base-flanges and adapted to be contacted 80 thereby and support the same, inwardly-extending inclined flanges integral with the sides of the base-plate and extending over and fitting snugly upon the base-flanges, parallel side plates integral with the inner edges of the 85 inclined flanges and bearing snugly upon the webs, a block interposed between the side plates and integral therewith, said blocks being seated within the recesses in the ends of the webs, and webs integral with and interposed between the side plates and their flanges. 90

In testimony whereof I affix my signature in presence of two witnesses.

AMDY CHRESTENSEN.
